SPINNING BOBBIN AND HOLDER FOR RAYON
SPINNING MACHINES

Theodor Grauer, Horn, Thurgau, Switzerland, assignor to the firm Feldmuehle A. G. vorm. Loeb, Schoenfeld & Co. Rorschach, Rorschach, Switzerland

Application April 15, 1938, Serial No. 202,341
In Germany March 3, 1937

14 Claims. (Cl. 242—46.6)

This invention relates to bobbins and holders therefor.

Known bobbin holders must be placed in the bobbin with little play, with disadvantageous results in that the holder grips the bobbin tightly so that the wound rayon cannot be removed without damage or at any rate only with difficulty. If, on the other hand, play is left between the bobbin and the holder then the bobbin has, during its rotation, no fast grip and thus knocks, runs eccentrically and even rebounds.

The present invention discloses a novel form of bobbin in combination with its holder, which makes it possible for the bobbin to be secured on the holder with a determined amount of play, but nevertheless ensuring an absolute fast grip of the bobbin thereon, so that the latter can neither knock nor move centrifugally.

A bobbin holder for artificial silk spinning machines according to the invention is characterised in that the inner sleeve of the holder is constricted near its central part like a cylindrical handle and the bobbin is secured to the holder by means of cams one of which is yielding, one series of cams being pressed against a rear cylindrical part and the other against a forward conical part of the bobbin.

It is an object of the present invention to provide an economical, efficient and practical bobbin and holder therefor, both bobbin and holder having cooperating means whereby the bobbin is frictionally secured on the holder to assure good grip of the bobbin thereon and at the same time providing the required play therebetween to enable relative separation of bobbin and holder.

This and other objects and advantages will become more apparent from the following description taken in connection with the accompanying drawing in which:

Fig. 1 is a longitudinal section through the bobbin and holder on the line 1—1 of Fig. 2, which latter figure is a cross section of the same parts on the line 2—2 in Fig. 1.

The holder 1 is secured on the spindle 3 by means of a set screw 2 and carries a hollow cylindrical attachment 4 in the inside of which is disposed a two-armed lever 5 supported by a spring 6 one end of which projects within bore 5a of lever 5 whereas the other end of which rests with said attachment 4. The two cheeks or cams 8 and 9 of the lever 5 extend through corresponding slots 8a, 9a of the hollow cylinder attachment 4 and press outwardly against the sleeve 1a of the bobbin 7. The bridge 10 on the cylinder attachment 4 prevents the said cams

of the two-armed lever 5 from projection too far outwardly. The cams 8 and 9 have respective bevelled surfaces 11 and 12 in order that they may frictionally engage the seat surfaces of said sleeve 1a of bobbin 7 with little resistance.

According to the invention, a special construction is provided for the sleeve 1a of bobbin 7. Said sleeve 1a is totally independent of the construction of the outer sleeve frame 7b, irrespective whether or not a rigid or an expansible bobbin 7 be concerned. Said frame which forms a skeleton sleeve, comprises the longitudinal bars 1e engageable with and resting on the end wings 1c, 1d, respectively. The end portions 19, 19a of said sleeve 1a are tapered or converge towards the center part 19b of said sleeve and terminate at each end thereof in a cylindrical or approximately cylindrical section 19c, 19d. This construction of the inner sleeve 1a ensures, in combination with the co-operating bobbin holder 4 a secure holding means for bobbin 7. The cam 8 of the lever 5 of the bobbin holder 4 (Fig. 1) presses against the inner cylindrical section 19c of the bobbin sleeve 1a while the other cam 9, adjacent the free end of holder 4, engages the bobbin sleeve 1a at the end portion 19 of sleeve 1a and so urges it towards the shaft 3. This latter cam 9 protrudes only so far from the holder 4 that it contacts with the converging end portion 19, while sufficient space is left for the bobbin 7 to be taken hold of with the hand by the spinner for the purpose of removing it.

In applying the bobbin to the holder heretofore, it has been usual for the bobbin to be pushed along the holder 4 until further movement of said bobbin is resisted. This resistance or stoppage of movement occurs when the bobbin edge 17 (Fig. 1) comes into contact with a suitable abutment of the bobbin holder. This produces the serious disadvantage that the usually well polished or varnished edges of the bobbin become damaged by these contacts and permit the thread to slip off.

The present invention aims at preventing this and, to this end, the parts 16, 20 and 21 of the bobbin 7 and of the holder 4 which come into contact with one another, are located when assembled, within the bobbin and so never come into contact with the silk thread.

The endeavour to protect the edges 13 and 14 and keep them always smooth and undamaged, so that the thread wound between them in a known manner is (15, Fig. 1) not injured, has further led to the provision of auxiliary edges 17, 18. The bobbin can then be stood up on these

edges 17, 18 respectively, and not on the edges 13, 14. Damage of the auxiliary edges cannot harm the thread. The real edges 13 and 14 are thus protected and remain always smooth and the spinning of the silk can proceed without damage to the thread and without a protective cap being necessary.

On the rear end of the cylindrical part 4 of the bobbin holder 4 there are fixedly provided at least two cams a' , a^2 , and likewise at the forward or free end of said holder at least two cams b' , b^2 . These fixed cams give in combination with the yielding cams 8 and 9 of the U-shaped member or two-armed lever 5 a secure seating for the bobbin sleeve 7a at the inner surface thereof, whereby said bobbin cannot move centrifugally or be projected forwardly. Especially cam 9 prevents this forward movement, since it presses on the inner converging seating surface provided on end portion 19.

According to the invention, bobbin 7 is held by yielding, pressure members or cams 8, 9 and also by the forwardly disposed rigid pressure members or cams b' , b^2 .

Hollow attachment 4 has two inwardly projecting lugs x to limit lateral movement of U-shaped member or lever 5 therewithin.

Having thus described the invention what is claimed as new and desired to be secured by Letters Patent, is:

1. A device of the character described comprising in combination a bobbin for artificial silk, and a holder for said bobbin, said bobbin including a sleeve having an inner surface, said surface being provided with a cylindrical intermediate part and a substantially outwardly flaring end portion extending from either end of said intermediate part, said holder including cam means frictionally engageable with said sleeve, at least one of said cam means being yieldably supported in said holder so as to engage one of said end portions when said holder is inserted through the other of said end portions into said sleeve.

2. A device of the character described comprising in combination a bobbin for artificial silk, and a holder for said bobbin, said bobbin including a sleeve having an inner surface, said surface being provided with a cylindrical intermediate part, a substantially outwardly flaring end portion extending from either end of said intermediate part, and a cylindrical section at the end of each flaring end portion, said holder including spaced apart series of cam means frictionally engageable with said sleeve, at least one of said cam means being yieldably supported in said holder so as to engage one of said end portions when said holder is inserted through the other of said end portions into said sleeve, said one of said cam means being seated with the other of said series of said cam means on said cylindrical section at the end of said other of said end portions.

3. A device of the character described comprising in combination a bobbin for artificial silk, and a holder for said bobbin having a free end, said bobbin comprising a sleeve having an inner surface, said surface being provided with an intermediate part and a substantially diverging end portion extending from either end of said intermediate part, said holder comprising an intermediate part, and means at either end of said intermediate part of said holder, said means being frictionally engageable with said sleeve, at least one of said means being yieldably projecting

from within said holder so as to engage one of said end portions of said sleeve when said holder is inserted through the other of said end portions into said sleeve.

5. A device of the character described comprising in combination a bobbin for artificial silk, and a holder for said bobbin comprising a sleeve having an inner surface, said surface being provided with a substantially cylindrical intermediate part and an end portion including a substantially cylindrical section adjacent the outer end of each end portion, said end portions substantially converging from said outer ends toward said intermediate part, said holder comprising an intermediate part, and a series of cam means at either end of said intermediate part of said holder, said cam means being frictionally engageable with said sleeve, at least one of said cam means of one of said series being yieldably held at said holder and engageable with one of said end portions when said holder is inserted through the other of said end portions into said sleeve and seated with the other of said series of said cam means on said cylindrical section at the end of said other of said end portions.

10. A device of the character described comprising in combination a bobbin, and a holder for said bobbin, said bobbin including a sleeve having an inner surface, said inner surface being provided with an intermediate part and an end portion diverging from either end of said intermediate part, each of said end portions being provided with a cylindrical section at the free end thereof, said holder comprising an intermediate part, and means at either end of said intermediate holder part, said means at one end of said holder part being frictionally engageable with one of said end portions of said sleeve, said means at the other side of said holder part being frictionally engageable with said cylindrical section of the other end portion of said sleeve.

15. A device of the character described comprising in combination a bobbin, and a holder for said bobbin, said bobbin including a sleeve having an inner surface, said inner surface being provided with an intermediate part and an end portion diverging from either end of said intermediate part, each of said end portions being provided with cylindrical sections at the free end thereof, said holder comprising an intermediate part, and means at either end of said intermediate holder part, said means at one end of said holder part being frictionally engageable with one of said end portions of said sleeve, said means at the other end of said holder part being frictionally engageable with said cylindrical section of the other end portion of said sleeve, one of said means at one end of said holder part and at the other end of said holder part being resiliently journaled thereat.

20. A device of the character described comprising in combination a bobbin, and a holder for said bobbin, said bobbin including a sleeve having an inner surface, said inner surface being provided with an intermediate part and an end portion divergingly extending from either end of said intermediate part, each of said end portions being provided with a cylindrical section at the free end thereof, said holder comprising an intermediate part, and means at either end of said intermediate holder part, said means at one end of said holder part being frictionally engageable with one of said end portions of said sleeve, said means at the other end of said holder part being frictionally engageable with said cylindrical

section of the other end portion of said sleeve, one of said means at one end of said holder part, and an adjacent means at the other end of said holder part projecting both from within said holder and being resiliently supported therein.

8. A device of the character described comprising in combination a bobbin, and a holder for said bobbin, said bobbin including a sleeve having an inner surface, said inner surface being provided with an intermediate part and an end portion divergently extending from each end of said intermediate part, each of said end portions being provided with a cylindrical section at the free end thereof, said holder comprising an intermediate part, and friction means at each end of said intermediate holder part, said friction means at one end of said holder part being engageable with one of said end portions of said sleeve, said friction means at the other end of said holder part being engageable with said cylindrical section of the other end portion of said sleeve, one of said means at one end of said holder part and an adjacent means at the other end of said holder part being interconnected within said holder and protruding with their free ends through respective openings of said holder for engagement with one of said end portions and said cylindrical section of the other end portion of said sleeve, respectively.

9. A device of the character described comprising a bobbin for artificial silk, said bobbin being provided with a sleeve having at its inner surface end portions substantially diverging from the center part of said surface toward the ends thereof, a holder for said bobbin, and spaced apart series of cam means in said holder for frictional engagement with said sleeve surface, one cam of one series being interconnected with one cam of the other series within said holder and being resiliently supported at the interconnection of said cams, each of said one cam protruding from within said holder through respective openings of said holder toward and contacting said end portions of said sleeve, respectively.

10. A device of the character described comprising a bobbin for artificial silk, said bobbin having a sleeve provided with substantially slanting end portions at the inner surface thereof, a cylindrical section at each end of said end portions, a hollow holder for said bobbin projectable within said sleeve and frictionally engageable within said sleeve, and spaced apart series of cam means at said holder for engagement with one of said cylindrical sections and with one of said slanting end portions, respectively, at least two cams of each series being rigidly connected with said holder.

11. A device of the character described comprising a bobbin for artificial silk, said bobbin

having a sleeve provided with frictionally engageable portions at the inner surface thereof, said portions substantially converging from each end of said surface toward the center part of said surface, a holder for said bobbin for coupling with said sleeve at said inner surface, and spaced apart series of coupling means projecting from said holder and positioned thereat so as to assure respective engagement of said coupling means with said sleeve portions, said coupling means of each series being symmetrically disposed with respect to the circumference of said holder.

12. A device of the character described comprising a bobbin for artificial silk, said bobbin having a sleeve provided with frictionally engageable portions at the inner surface thereof, said portions substantially converging from each end of said surface toward the center part of said surface, a bobbin holder for coupling with said sleeve at said inner surface, and spaced apart series of coupling means projecting from said holder and positioned thereat so as to assure respective engagement of said coupling means with said sleeve portions.

13. A device of the character described comprising a bobbin for artificial silk, said bobbin having a sleeve provided with a frictionally engageable inner surface, said surface being substantially slanting from each end thereof toward its center, a bobbin holder for coupling with said sleeve at said inner surface, and spaced apart series of coupling means projecting from said holder and positioned thereat so as to assure respective engagement of said coupling means with said sleeve surface.

14. A device of the character described comprising a bobbin for artificial silk, said bobbin having a sleeve provided with substantially slanting end portions at the inner surface thereof, a cylindrical section at the free end of each end portion, said portions extending from said sections, respectively, toward the center of said surface, a holder for said bobbin projectable within said sleeve and engageable therewith, and spaced apart series of cam means at said holder for frictional engagement with one of said cylindrical sections and one of said slanting end portions, respectively, one cam of each series being resiliently supported in said holder, each of said cam means of one series being provided with a cylindrical surface portion, while each of said cam means of another series being formed with a conical surface portion, whereby upon engagement of said holder with said bobbin, said cam means of said one series contact with said one of said cylindrical sections and said cam means of said other series contact with said one of said slanting portions.

THEODOR GRAUER.
